UNITED STATES PATENT OFFICE.

MARTIN GERBER, OF IOWA CITY, IOWA.

AUTOMOBILE-RADIATOR CASING.

1,348,710.

Specification of Letters Patent.

Patented Aug. 3, 1920.

Application filed February 12, 1920. Serial No. 358,113.

To all whom it may concern:

Be it known that I, MARTIN GERBER, citizen of the United States, residing at Iowa City, in the county of Johnson and State of 5 Iowa, have invented certain new and useful Improvements in Automobile-Radiator Casings, of which the following is a specification.

This invention relates to automobile radiator casings, and belongs to that class or 10 type of structures forming parts of motor vehicles as customarily constructed which are attached to the frame members of the machine, while the radiator itself is supported within the casing free from actual, 15 direct attachment to the frame, and capable of a slight independent movement within the casing, the purpose being to defend the radiator itself from forcible, distorting twists, 20 jars and the like consequent breakage and leaking.

It is the object of this invention to produce a supporting casing of the character 25 stated having parts of special construction and arrangement whereby it is believed a particularly cheap, easily applied, and durable as well as effective protector for the contained radiator itself is built up, and one that may be put together and taken apart 30 quickly and without tools fashioned for the purpose only.

In the accompanying drawings the construction of each part, and the arrangement 35 of the parts with respect to each other are illustrated. Figure 1 represents a side view of all the parts assembled, and shows a radiator held in the casing. Fig. 2 is a front view of the parts set forth in Fig. 1. Fig. 3 is a cross-section on the broken line 3—3 40 of Fig. 10 of the trough-like member of the bottom portion of this invention. Fig. 4 is a cross-section on the broken line 4—4 of Fig. 10 of the trough-like member of the bottom of this invention. Fig. 5 is a rear 45 view of the top portion of this invention. Fig. 6 is a front view of one of the side members. Fig. 7 is a vertical cross-section of the top portion taken on the broken line 7—7 of Fig. 5. Fig. 8 is a side or flatwise 50 view of one of the side members. Fig. 9 is a horizontal cross-section of the side member taken on the broken line 9—9 of Fig. 8. Fig. 10 is a rear view of the bottom portion of this invention.

Throughout the drawings and description, 55 the same letter is used to refer to the same part.

Considering the drawings, a radiator A, which has the usual cooling grated cooling structure a, inflow connection B, and outflow 60 pipe b, is shown in a casing made in accordance with this invention and comprising a top portion referred to generally by the letter C. The top portion has a curved front or apron D, and a collar d at the top for the 65 passage of the filler tube E, of the radiator, which has the usual cap e. As best illustrated in Fig. 7, the top portion C has the side walls F and the back wall f. The top portion has also the downwardly extending 70 positioning lugs G and g, to be again mentioned.

There are two side members, h and h', and, as best set out in Figs. 6 and 8, each side member has at the top corner a recess 75 or socket. These are marked H and H'. The positioning lugs G and g of the top portion C engage these sockets when the parts are assembled. To stiffen the side members, which, like the top portion C, are made of 80 sheet metal each is provided with a longitudinal stiffening corrugation such as the corrugation J, projecting externally when the parts are assembled and the top C has a like external corrugation j', which lies in line 85 with the corrugations of the sides when the parts are placed properly together. The top C and the side members are furnished with suitable brackets or flanges K, k and L, l, through which are passed bolts M and m 90 to secure the top and sides together.

As best shown in Fig. 1, the top portion C has a strip of surface N provided with rivet holes, and the side members have strips running lengthwise also having the rivet 95 holes, by means of which the hood, not shown may be attached to the assembled parts of this invention in the same manner as it would be otherwise to the exterior of a radiator when no protective casing such as 100 this invention is provided. n marks a side strip.

Figs. 4 and 10 best set forth the bottom member of this invention. The angular end pieces O and P are castings, and relatively 105 rigid, and they are connected by a trough-like sheet metal member Q. Near one end the trough Q has a depending, curved, hol-

low portion open to the rear, to receive the outflow pipe *b* of the radiator *A*. This hollow portion is marked *R* and is shown in section in Fig. 4. In addition, the floor of 5 the trough *Q* has a sunken and inclined portion *r*. On the left side, considering Fig. 10, the sunken portion *r* extends from the left hand end of the trough *Q* to the drip opening *S*, which is shown in Fig. 3. On the 10 right of the drip opening the sunken portion extends downwardly from the depending hollow portion *R* to the drip opening. At their lower ends the side members have the flanges *T* and *t*, and the cast metal ends of 15 the bottom member have the corresponding flanges *U* and *u* by which the bottom member and the sides may be connected. In practice the bolt hole through these flanges is set back one-fourth inch from the main middle 20 line and fits a spring bolt, not shown, on the side member of the frame on each side of the vehicle.

In Fig. 9 it will be noted that the front edge portion of the side member *h* is turned 25 inwardly and is slightly curved, and in Figs. 3 and 4 it will be seen that the front wall of the trough *Q* is also somewhat curved. The rear wall *s* of the trough is inclined outwardly. The purpose of the 30 curving front edge portion of the side members, and of the front wall of the trough *Q* is to effect a snug fit between the front of the radiator and the edges of the side members and bottom member of this invention. The close contact attained prevents 35 the entrance of mud and dirt or other foreign matter between the casing and the radiator. The inclination of the rear wall *s* of the trough permits some clearance and 40 guides the bottom of the radiator toward the front wall of the trough *Q*.

In the operation of this invention, the radiator *A* is placed within the casing, as is believed to be clear from the foregoing 45 explanation. The casing is attached directly to the frame of the vehicle and receives directly any twists or distorting jerks during the progress of the vehicle. The radiator itself being unattached has a limited 50 movement within the casing and is in that way protected from injury. As will be understood, any leakage within the casing escapes by way of the drip opening *S*.

Having now described this invention, and 55 explained the mode of its operation, what I claim and desire to secure by Letters Patent of the United States is:—

1. In a radiator casing, the combination with a sheet metal top portion having a 60 filler tube collar and a front apron, the said

top portion having an externally projecting stiffening corrugation extending from side to side thereof and in rear of the said collar, of vertical sheet metal side members each having a stiffening corrugation extending longitudinally and in line with the said corrugation of the top when the parts are assembled, means for securing the sides and top together, a bottom member comprising angular ends and a sheet metal trough-like member connecting the said ends, the said trough having a depending, curved, hollow portion open rearwardly to receive the outflow pipe of a radiator, and means for connecting the sides and the said ends of the 75 bottom.

2. In a radiator casing, the combination with a sheet metal top portion having an externally projecting stiffening corrugation extending from side to side thereof and a 80 filler tube collar and front apron, of vertical sheet metal side members each having a stiffening corrugation extending longitudinally and in line with the said corrugation of the top when the parts are assembled, 85 means for securing the said sides and top together, a bottom member comprising angular ends and a sheet metal trough-like member connected with the said ends, the said bottom having a depending, curved, 90 hollow portion open rearwardly to receive the outflow pipe of a radiator, the floor of the said trough-like member having a drip opening and a sunken portion extending from one end of the trough downwardly to 95 the said opening, and downwardly from the said depending, curved hollow portion to the said drip opening, and means for connecting the said sides and the said angular ends of the bottom.

3. In a radiator casing, the combination with a sheet metal top portion having a filler tube collar and a front apron, of vertical sheet metal side members each having an inwardly turned front edge portion, 105 means for securing the sides and top together, a bottom member comprising angular ends and a sheet metal trough-like member connecting the said ends, the said trough having a depending, curved, hollow 110 portion open rearwardly to receive the outflow pipe of a radiator, the said trough having a drip opening and sunken portions leading to said opening, the said trough having an inwardly turned front wall and an 115 outwardly inclined back wall, and means for securing the bottom and sides together.

In testimony whereof I affix my signature.

MARTIN GERBER.
